US0D1049290S

(12) **United States Design Patent** (10) **Patent No.:** **US D1,049,290 S**
(45) **Date of Patent:** **** Oct. 29, 2024**

(54) **RECREATIONAL PAD FOR SPRAYING WATER**

(71) Applicant: **SDS Asia Limited, BVI #1748971, Hong Kong (CN)**

(72) Inventor: **Jeff Baack, Omaha, NE (US)**

(73) Assignee: **SDS Asia Limited, BVI #1748971, Central Hong Kong (CN)**

(**) Term: **15 Years**

(21) Appl. No.: **29/887,676**

(22) Filed: **Mar. 23, 2023**

(51) **LOC (14) Cl. 21-03**

(52) **U.S. Cl. USPC D21/814; D21/811; D21/815; D21/818; D21/819**

(57) **CLAIM**

The ornamental design for a recreational pad for spraying water, as shown and described.

DESCRIPTION

FIG. 1 is a perspective view of a recreational pad for spraying water, showing my new design;

FIG. 2 is a front elevation view thereof;

FIG. 3 is a rear elevation view thereof

FIG. 4 is a right side view thereof;

FIG. 5 is a left side view thereof;

FIG. 6 is a top plan view thereof; and,

FIG. 7 is a bottom plan elevation view thereof.

The broken lines illustrate portions of the recreational pad for spraying water that form no part of the claimed design.

1 Claim, 7 Drawing Sheets
